UNITED STATES PATENT OFFICE.

MARSHALL R. BRITTON AND CHESTER K. BRITTON, OF GRANTS PASS, OREGON.

DOORCHECK.

Application filed July 24, 1922. Serial No. 577,145.

To all whom it may concern:

Be it known that we, MARSHALL R. BRITTON and CHESTER K. BRITTON, citizens of the United States, residing at Grants Pass, in the county of Josephine and State of Oregon, have invented certain new and useful Improvements in Doorchecks, of which the following is a specification.

This invention relates to improvements in door checks.

The primary object of this invention is the provision of a check device, which may be utilized in connection with closure members, such as doors, in the facile retention of the closure member in the position in which it is desired that the same be supported.

An important object of the invention is the provision of a relatively simple and compact door check, which is particularly well adapted for large doors, such as garage doors, and which is novel in so far as the co-operative construction and arrangement of parts is concerned.

Other objects and advantages of this invention will be apparent during the course of the following detailed description.

In the accompanying drawing, forming a part of this specification, and wherein similar reference characters designate corresponding parts throughout the several views,

Figure 1 is a perspective view of a closure member, showing the improved door check member as located therein and in position for holding the closure member in a desired manner.

Figure 2 is a fragmentary view, partly in section, showing the cooperative relation of the improved door check details and the closure member.

Figure 3 is a front elevation of certain details of the improved door check.

In the drawing, wherein for the purpose of illustration is shown but the preferred embodiment of this invention, the letter A designates the improved door check adapted for use upon a swinging closure member B. The improved door check preferably comprises an attaching bracket 10, closure retaining element 11; spring 12; and means 13 for attaching of the door check A to the closure member B.

The attaching bracket is preferably of metal, and may be cast or bent to provide a flat rectangular shaped attaching portion 15 having the walls 16 and 17 bent outwardly

therefrom in the same direction and preferably extending at right angles to the plane defined by the attaching portion 15. These flange walls 16 and 17 extend from one end of the attaching bracket plate 15 to the other end and gradually slope outwardly from the upper and lower marginal edges 18 and 19 of the attaching plate 15, so that the intermediate portions of the walls 16 and 17 are of greatest width midway of the edges 18 and 19, as can readily be seen from Figures 1 and 2 of the drawings. A detachable bolt member 25 is preferably disposed transversely between the walls 16 and 17 of the attaching bracket 10, and engaged intermediate the ends of said walls through the portions of said walls 16 and 17 which are greatest removed from the attaching plate portion 15.

The closure member retaining element 11 is of spike like formation, and includes the relatively long shank 27 which is pointed, as at 28, at one end for ground engaging purposes, and which is provided with a rounded head 29 upon its other end. At the juncture of the rounded end 29 and the shank portion 27 of the element 11, an aperture 30 is provided for pivotally receiving the bolt member 25, so that the closure member engaging element 11 may be oscillatively connected to the attaching bracket 10 with the rounded head portion 29 extending into the pocket of the bracket 10 intermediate the side walls 16 and 17. The head 29 is provided with a rounded margin 31, which is of cam like formation with respect to the pivot point 25 of the member 11, and is adapted for cooperation upon the spring 12, in a manner to be subsequently described.

The means 13 preferably comprises upper and lower bolts 35 and 36 respectively, which are adapted for cooperation in the apertures 37 and 38 respectively, disposed in the attaching plate portion 15 of the attaching bracket 10, adjacent the top and bottom marginal edges 18 and 19 respectively thereof. In the disposition of these bolt members 35 and 36 the heads 39 thereof extend outwardly from the attaching plate 15. The spring member 12 is of a good grade of spring steel and is of arcuate formation, with the ends 41 and 42 thereof in sliding contact upon the exposed surface of the attaching plate 15, adjacent the projecting heads 39 of the bolts 35 and 36 re-

spectively. The bowed portion 43 of the spring member 12 extends outwardly from the plate 15 in spaced relation thereto and toward the head 29 of the closure member 5 retaining element 11, and with which head 29 the bolt portion 43 of the said spring is always in contact.

In the attachment of the improved device upon the closure member B, the bolts 35 10 and 36 are disposed in the attaching bracket 10 as above described, and inserted through suitable openings in the closure member B, so that nuts 45 may be adjusted upon said bolts 35 and 36 to secure the attaching plate 15 of the bracket 10 flat upon a surface 15 of the closure member B with the walls 16 and 17 substantially in vertical position. In this position, the retaining spike 11 may be swung in a vertical plane. If it is the desire 20 of a person to retain the closure member B in a set position, that person merely swings the spike 11 downwardly until the point 28 thereof is in engagement with the ground surface. In this position, the head portion 25 29 thereof is in engagement with the bolt portion 43 of the spring 12, which maintains the same under compression, so that said spring 12 acting upon the head 29 will maintain the spike or retaining member 11 in 30 a position against liability of displacement. As above mentioned, the rounded surface 31 of the member 11 has a cam action upon the spring 12, and as the operator swings the same upwardly from the position illustrated 35 in Figure 2, it can readily be seen that the bowed portion 43 of the spring member 12 will be further depressed toward the attaching plate 15 until the member 11 is in a horizontal position, and in which position 40 the spring 12 is depressed to its farthest point. Upon upward swinging of the member 11 from its horizontal position, it can readily be understood that the action of the spring 12 upon the head 29 will be such as 45 to retain the member 11 in any position in which the same may be placed and against liability of displacement.

From the foregoing, it can be seen that a 50 relatively simple door check has been provided, in which the retaining elements 35 and 36 thereof, cooperate not only in the retention of the bracket 10 upon the supporting closure member B, but which cooperate with the sliding ends of the spring 55 12 in the retention of said spring 12 in proper position upon the attaching bracket. The side walls 16 and 17, of course, cooperate with the spring 12 in maintaining an accurate placement of the same in the pocket 60 intermediate said walls 16 and 17. By reason of the loose disposition of the spring 12,

the same may be readily detached, either for replacement or manual adjustment so that the same will exert a proper tension upon the member 11.

65

Various changes in the shape, size and arrangement of parts may be made to the form of the invention herein shown and described, without departing from the spirit of the invention or the scope of the claims.

70

We claim:

1. A door check, comprising an attaching bracket including a relatively flat plate provided with side walls extending outwardly substantially at right angles thereto throughout the length of said plate, said walls being of greatest width intermediate the ends of said plate, a pin member connected transversely between said side walls and in spaced relation directly opposite the plate substantially midway of its ends, a retaining lever pivoted to said pin and including an elongated portion extending outwardly from said attaching bracket and having a rounded cam head portion extending 80 opposite from said elongated portion of said lever into said attaching bracket intermediate the side flanges thereof, a bowed spring having the ends thereof in sliding engagement with the plate of said attaching bracket 90 and the bowed central portion thereof in engagement with said cam head of the lever for normally maintaining said lever in a position in which the same is set.

85

2. In a door check, the combination with 95 a closure member, of an attaching bracket including a relatively flat portion apertured at its ends, bolt members for disposition in said apertures for attaching said brackets to said closure member, the heads of said bolts extending outwardly from the exposed surface of said plate, said attaching bracket having side walls extending outwardly thereof substantially at right angles thereto, a lever having a spherical like head, means 10 pivoting said lever to the outer portions of said side walls at the juncture point of said spherical head and the shank of said lever, and an arcuate spring member adapted for loose disposition within said attaching 110 bracket with the ends thereof in sliding contact with the plate portion of said bracket and disposed adjacent the heads of said attaching bolts, the intermediate portion of said spring being in normal engagement 115 with the spherical head of said lever whereby the spring is normally under tension to force said lever in a position in which the same is set.
